UNITED STATES PATENT OFFICE.

JOHN ELLENBECKER, OF PORT WASHINGTON, WISCONSIN.

REVOLVING CHAIR.

SPECIFICATION forming part of Letters Patent No. 655,701, dated August 14, 1900.

Application filed July 2, 1900. Serial No. 22,252. (No model.)

To all whom it may concern:

Be it known that I, JOHN ELLENBECKER, of Port Washington, in the county of Ozaukee and State of Wisconsin, have invented a new and useful Improvement in Revolving Chairs, of which the following is a description, reference being had to the accompanying drawings, which are a part of this specification.

My invention relates to improved devices adapted for use with a chair or stool to facilitate the raising or lowering of the seat and to permit of the rotation or swinging around of the seat in position freely without thereby in any manner raising or lowering the seat.

The invention consists of the devices and their combinations, as herein described and claimed, or the equivalents thereof.

In the drawings, Figure 1 is a vertical section of my improved devices to be employed in a revolving chair, adapted for raising and lowering the seat and for permitting the seat to be rotated without raising or lowering it. Fig. 2 is a top plan view of the nut turning on the spindle for raising and lowering the seat. Fig. 3 is a top plan view of the hub in which the spindle turns and which hub is supported by the legs of the chair. Figs. 4 and 5 are respectively a top plan view and a side elevation of a sleeve that fits about the spindle within the nut.

In the drawings, 6 is a hub which receives the inner ends of the legs of the chair in sockets therein and is secured to those legs and serves to support the chair-seat thereon by means of the devices hereinafter described. The hub 6 is provided with a central longitudinal bore cylindrical in form and of equal diameter throughout its length, in which the screw-threaded spindle 7 fits revolvably and adjustable vertically. This hub 6 has radially-extending flanges 8 at the top of the body of the hub, which flanges rest on the upper surfaces of the legs of the chair and are secured to those legs by means of screws through the apertures shown therefor. This hub is also provided with a tubular neck 9, extending upwardly from the body of the hub above the flanges 8. This neck 9 is provided with an annular groove 10, cut in its exterior surface medially. A sleeve 11, fitted loosely about the spindle 7, rests on the upper end of the neck 9. This sleeve is pref-

erably of substantially the same diametrical size and thickness as the neck 9. This sleeve 11 is provided with a longitudinally-disposed tongue 12, projecting inwardly from its inner surface, which tongue enters and is slideable endwise in a longitudinal groove 13 in the spindle 7. The construction holds the sleeve 11 to rotation with the spindle 7, but permits its movement freely longitudinally thereon. A nut 14 turns by its thread on the spindle 7 and is advisably provided with a hand-wheel 15 for conveniently rotating the nut on the spindle for raising or lowering the seat of the chair or stool. This nut 14 is elongated in the direction of the length of the spindle 7, and its axial bore is enlarged in the lower portion thereof, forming a chamber adapted to receive therein the sleeve 11 and the neck 9. The construction is such that the annular shoulder 16, formed at the lower end of the screw-thread in the nut 14 and at the upper end of the lower chambered portion of the nut, rests on the top of the sleeve 11, and the peripheral wall of the chamber fits loosely about the sleeve and the neck. This construction permits of the free rotation of the nut and the spindle on the top of the sleeve 11, whereby the seat of the chair or stool which is fixed on the spindle-head 17 may be freely rotated without its being raised or lowered.

Advisably a little boss 18 is formed on the under surface of the shoulder 16, which is adapted to enter a slight recess or depression 19 in the top edge of the sleeve 11. This recess is formed with inclined walls, and the construction is adapted to secure the chair-seat in position against too free revolution or against accidentally or undesirably rotating, the resistance to such rotation occurring by reason of the boss 18 entering the depression 19, being such only as to prevent such accidental or undesirable rotation of the seat, while permitting its rotation freely under slightly-additional force applied thereto, directed to secure rotation of the chair-seat. A pin 20 through the wall of the chamber of the nut 14 enters the groove 10 and prevents the removal of the spindle and the nut from the hub except by withdrawing the pin. The pin is advisably screw-threaded, so as to secure it releasably in place, and the groove 10 is of

such width vertically as to provide sufficient play of the pin 20 therein to permit of the boss 18 being raised onto the top of the sleeve 11 out of the depression 19.

5 What I claim as my invention is—

1. A revolving-seat iron, comprising a hub provided with an upwardly-projecting tubular neck, a screw-threaded spindle rotatable freely in the hub and its neck, a sleeve resting on said neck and provided with an interior tongue projecting into a longitudinal groove in the spindle, and a nut turning by its thread on the spindle above the sleeve and resting on the sleeve and encircling said sleeve and said neck.

2. A revolving-seat iron, comprising a hub, a tubular neck projecting above the body of the hub, the hub and neck having an axial cylindrical bore of equal diameter throughout its length, a screw-threaded spindle fitted and rotatable freely in the hub and provided with a longitudinal groove, a sleeve resting on the neck and provided with a tongue entering the groove in the spindle, a nut turning by its thread on the spindle and provided with an annular shoulder at the lower end of its thread which shoulder rests on the sleeve,

1 said nut also encircling said neck, and means securing the nut to the neck revolvably and releasably.

30

3. In combination, a chair-hub provided with an upwardly-projecting tubular neck, the neck having an annular exterior groove therein and the hub and neck having an axial cylindrical bore of equal diameter throughout its length, a screw-threaded spindle provided with a longitudinal groove fitted and rotatable freely in the hub and its neck, a sleeve resting on the neck and provided with a tongue projecting freely into the groove in the spindle and having a depression in its upper edge, a nut turning by its thread on the spindle and resting on the sleeve and provided with a boss adapted to enter the depression in the sleeve, said nut being extended downwardly about 45 the sleeve and the neck, and a pin through the wall of the nut entering the groove about the neck of the hub.

In testimony whereof I affix my signature in presence of two witnesses.

JOHN ELLENBECKER.
